VALVE ACTION MECHANISM FOR WIND INSTRUMENTS

Charles E. Bryant, Elkhorn, Wis., assignor to
Frank Holton and Company, Elkhorn, Wis., a
corporation of Wisconsin

Application May 14, 1934, Serial No. 725,543

6 Claims. (Cl. 84—385)

My invention relates to improvements in valve action mechanisms for wind instruments.

The object of my invention is to provide an actuating mechanism for a valve lever of a musical instrument whereby to provide a positive, light, fast action.

Another object of my invention is to provide an octave valve key action for a wind instrument wherein the manipulation of the key by the player causes the valve to open by reason of positive lever action.

In the drawing:

Figure 1 is a side elevation of a saxophone in which a preferred form of my new valve actuating mechanism is incorporated.

Figure 2 is a section on line 2—2 of Fig. 1.

Like parts are designated by the same reference characters throughout the views.

In the drawing I have shown my valve actuating mechanism in the form in which it is incorporated in a saxophone 10 which is provided with the usual goose-neck 11 and main pipe 12. In the goose-neck 11 is an octave valve 13 closed by a pad 14 forming a part of a long lever 15 comprising the octave key which is fulcrumed at 16 and which is moved to normally closed position by spring 17. A ring 18 carried rigidly by the octave key 15 surrounds the goose-neck and extends peripherally to encompass the padded end 19 of an automatic octave key 20 forming one of the principal parts of my novel construction.

Those skilled in the art will be aware of the purpose of the octave key 15 and the opening and closing of the valve 13 which, when closed, causes the instrument to be pitched in the lower register and when opened causes the instrument to be pitched in the upper register. In my improved construction the spring 17 acting upon the octave key 15 tends to close the valve 13 by pressing the pad 14 thereupon and the pressure of the thumb of the player opens the valve by means of levers constituting the action now to be described.

The various elements of my new action are supported upon posts 21 to 25, inclusive, projecting from the pipe 12 forming the main body member of the saxophone. Tracing the motivating impulse of the pressure of the thumb of the player upon thumb piece 26, we find that the thumb key when pressed causes the thumb key shaft 27 to rotate upon an axis supported by posts 21 and 22. In its rotative movement, the thumb key shaft 27 swings the thumb key lever 28 which is provided at its tip with a ball 29.

The ball 29 is receivable in a socket 30 in one end of a link 31. At the other end of the link 31 is a socket 32 in which is receivable a ball 33 forming a part of post 23. The link 31 is integral with automatic octave key 20 which, as stated above, extends upwardly to its padded end 19 which abuts the interior surface of ring 18.

Below the link 31 the automatic octave key 20 extends downwardly a considerable distance to its lower extremity 34 where it is in a position to be overlayed by a finger 35 forming a part of the G key 36, which is normally in such a position as to cause the finger to bear upon the lower extremity 34 of the automatic octave key 20. The point of contact between the lower end 34 of the automatic octave key and the finger 35 becomes therefore a fulcrum about which the automatic octave key 20 swings when the ball 29 moves outwardly away from the main body 12 of the saxophone, and it is this outward action of the padded tip 19 of the automatic octave key 20 which causes the lower portion of the octave key 15 to be drawn in toward the goose-neck, and therefore causes the valve 13 to be opened when the pad 14 is lifted therefrom by the upper end of the octave key lever.

When the G key is pressed down and the finger 35 is therefore swung away from the body of the instrument, the fulcrum at 34 is effectively removed and movement of the thumb piece 26 will be ineffective to move the part 18 of the automatic octave key 20.

Attention is particularly called to the construction of the link 31 which is so deeply socketed at 30 as to permit of the insertion of a compression spring 37 to bear upon the ball 29 and therefore prevent undue looseness in the position of the ball 33 in socket 32 at the other end of the link. The link is therefore in such relation to the ball 29 and the ball 33 as to provide what may be termed universal motion of the link with respect to said balls and the link may be said to "float" between them. I have found that this socketed link form of action is extremely light, positive, and fast, and taken in conjunction with the change which I have made in the octave key 15 itself, provides for positive opening of the valve 13 even though the pad 14 may have stuck thereto in an interval of disuse of the instrument.

I claim:

1. An action mechanism for a musical instrument including a motivating lever provided with a ball tipped arm, a stationary member provided with a ball tipped arm and a motivated member

comprising a link socketed to receive said ball tips, and extending therebetween, one of said sockets in the link being provided with an inset spring.

- 5 2. The combination with a musical wind instrument provided with a ported opening to change the pitch thereof, of a lever with a pad for closing said opening, a finger key and lever to operate the pad lever, a stationary fulcrum, and
- 10 10 an intermediate lever to interact with the lever and provided with a floating link extending between the fulcrum and the finger key lever, said lever, said link and said fulcrum being interconnected by means of ball and socket connections, one of which is provided with a socket sufficiently elongated to provide for motion of the ball in the socket in the direction of the longitudinal axis of the link.
- 15 15 3. An action mechanism for a musical instrument including spaced members, one of which comprises a movable portion of the action, a link floated between the members and provided with ball and socket connection therewith, one of the ball and socket connections being provided with
- 20 20 25 a resilient member whereby to prevent loose and noisy interaction between the link and said members.
- 25 4. An action mechanism for a musical instrument including spaced members, a link between

the members and provided with a ball and socket connection therewith whereby to float the link between said members, one of said members being fixed and another of said members being mounted for rocking motion, the socket for the ball on the last mentioned member being deeply pocketed to permit of movement of the ball therein along a longitudinal axis of the link.

5 5. An action mechanism for a musical instrument including spaced members, one of said members comprising a fixed fulcrum and the other of said members comprising a rocking actuator, a link floated between the members and provided with sockets to receive the balls upon said spaced members, the socket to receive the ball of the rockable member being substantially deeper than the socket to receive the ball of the fixed member and a spring in the deeper socket whereby to urge the link against the ball of the fixed member.

10 6. In a musical instrument having action mechanism, an actuator lever, an actuated member comprising a floating link between said levers, and ball and socket connections between said link and said lever, one of the sockets being 15 deepened to permit of action longitudinal of the link.

20 25 CHARLES E. BRYANT.
